UNITED STATES PATENT OFFICE.

BRADNER L. HARRIS, OF DETROIT, MICHIGAN, ASSIGNOR OF THREE-FOURTHS
TO JAMES D. LEHMER, OF CINCINNATI, OHIO, AND FRANK H. ELLIS, OF
ST. LOUIS, MISSOURI.

GRIP FOR CABLE-RAILWAY CARS.

SPECIFICATION forming part of Letters Patent No. 394,539, dated December 11, 1888.

Application filed May 9, 1888. Serial No. 273,266. (No model.)

To all whom it may concern:

Be it known that I, BRADNER L. HARRIS, a citizen of the United States, residing at Detroit, in the county of Wayne and State of Michigan, have invented certain new and useful Improvements in Grips for Cable-Railway Cars, of which the following is a specification.

My present invention is an improvement on the grip for which, on the 3d day of January, 1888, Letters Patent of the United States were issued jointly to James D. Lehmer and myself, said Letters Patent being numbered 375,997; and it consists—

First. In providing means whereby the cable can readily be disengaged and thrown from the carrying-wheels and grip-frame, should an accident occur from any cause, as by reason of the cable-strands becoming loose, thereby endangering their catching in the gripping mechanism or frame and causing damage. These same remarks will apply to the ready manner in which the cable can be disengaged from the grip when the car is about to cross another cable.

Second. The facility with which the operating-lever can be worked without the operator changing his position or exercising an unusual reach.

Third. In providing mechanism whereby a double grip is obtained, and which can be used where either a switch or turn-table is employed—that is to say, in case of a switch, when the car is proceeding in one direction, one set of the binding-rollers will act, and when switched onto the return-track the cable will be thrown so as to be automatically brought into connection with the other set of binding-rollers.

These features, as well as others incidental thereto, will be understood from the description which I will give, and by reference to the accompanying drawings, forming part of my application, in which—

Figure 1 is an elevation of my grip and its attachments, showing the cable held between one set of the binding-rollers. Fig. 2 is also an elevation showing the cable held between the other set of rollers when the car is switched onto the return-track. Fig. 3 is an

enlarged view taken through the lower portion of Fig. 1 or 2, and shows the cable held between one set of the binding-rollers and in contact with the throw-outs, ready, if desired, to be disengaged from the grip. Fig. 4 is a view showing a portion of the actuating-lever and segment-rack. Fig. 5 is a cross-section taken through the line 5 5 of Fig. 4. Fig. 6 is also a cross-section taken through the line 6 6 of Fig. 1. Fig. 7 is a perspective view illustrating more clearly the formation of my double grip and the manner in which the levers that carry the binding-rollers are connected and operated.

The letter A represents the frame which carries the gripping mechanism. This frame is attached to the car in any convenient and durable manner. Its upper portion is segmental in shape, and is composed of duplicate pieces, which are connected together by the bolts b" in such manner as to leave a space between them, so that the lever L can be operated back and forth. This slot or space affords a guide and lateral guard for the said lever. This is seen more clearly by referring to Figs. 5 and 6. The teeth of this segment are peripheral, and, beginning at the middle thereof, diverge or run in opposite directions—that is to say, one side will have the teeth inclined in one direction, while the opposite is the case on the other.

P is a pawl for engaging with the teeth on the segment. This pawl through its round stem is connected by means of a swivel-joint to a spindle, C, which in turn is supported by the crank-lever F', pivoted on the operating-lever L. The lower portion of lever L is pivoted to the cross-plate O. Rigidly attached to the lever L is a collar, o', which embraces the swiveled spindle C, and between the collar and the swiveled connection and around the said spindle is a spring, p, which performs the operation of reseating the pawl when the drawing force from above is removed.

G is a collar embracing the lever L and the pawl P. This collar is movable and adapted to slide up and down the lever L, and its interior at the point where it embraces the pawl is squared or angular, in order to hold and

lock the pawl so that it may not slip out of its proper position.

5 *i i* are pins on either side of the lever L, and they are designed as a seat for the collar G and limit its drop. *t* is the knob by which the collar G is raised.

Suitably connected to the lower end of lever L is a link, Y, which at the point of connection is slotted, in order to permit the bolt or 10 rivet *f''* to have the proper freedom or play when being operated. The middle of this link Y is fulcrumed at *f'* to cross-bar H, which is above the slotted rail T. Either end of cross-bar H extends beyond the sides of the 15 grip-frame, where they are provided with handles which are utilized when the grip-frame and its affixed mechanism are to be removed from the cable conduit or tunnel. Suitably affixed to the lower end of link Y 20 are arms J K, to the outer ends of which in turn are connected levers M N, which are fulcrumed to the plate S at *h'* and *n'*, respectively.

It may be observed here that arms and 25 levers similar to J, K, M, and N are duplicated on the other side of plate S, and are operated similarly by lever L through the intermediate link, Y. This is shown in Figs. 1, 2, and 3, but more particularly in Fig. 7. The 30 duplicate levers are marked M' and N', while the binding-wheels which they carry are indicated by U' and V', while the two other binding-wheels are marked U and V, respectively, as shown in Fig. 1.

35 W is the cable, the arrow indicating the direction in which it is traveling.

a a' b b' represent the cable - carrying wheels properly secured in the frame to the cross-bar *s*, as shown.

40 Attached to the lower portion of the frame are what I would term "throw-outs" S' and D', each being also duplicated on the other side of the grip-frame. They are adapted to slide up and down, and may be held in position in any suitable manner, as by guide-pins 45 *c c* in connection with guard-irons *g g*, properly attached to cross-plate S, as shown. These throw-outs at their lower ends are bell-shaped on one side; or they may be in the 50 form of an incline plane, as seen more plainly and particularly in Fig. 3. The bottoms of these throw-outs, when they are in their normal positions, extend down below the cable, as seen in Figs. 1 and 2.

55 Throw-outs S' are provided with an arm, *n*, so that when the lever M is drawn up the roller U will strike and actuate it. Throw-outs D', however, which, considered by themselves, are just the same in construction as the others, 60 are somewhat differently actuated. To their upper ends are pivoted arms *g'*, which work on fulcrum *f*. As the lever N is forced down, the heel *y'* will be tilted back, striking the arm *g'* on its free end, thus throwing up the other 65 end, sufficient play being obtained through the medium of the slot at the pivotal point. This action will raise throw-out D', and in its rise

its incline will come into contact with the cable and act similarly and simultaneously with throw-out S', unloading the cable from the carrying-wheels and off the frame. Each throw-out is provided with a spring, as *l l*, which brings them back again to their normal positions when the lifting force is removed.

70 H' H' are chafing-plates, preferably of steel, which are securely attached to both sides of the frame A at the point where it strikes the slotted rail T. These chafing-irons are for the purpose of making the frame more durable, 80 and when they become worn out they can easily be removed and others inserted in their places.

75 *e e* are set-screws on which the grooved plate or bed P' rests. On this bed-plate the 85 cable between the carrying-wheels finds a resting spot. The set-screws *e* are inserted through the plate *s*, and as the plate is worn away by friction of the cable the degree of wear is compensated by raising the set-screws 90 to the desired height, and this action in turn raises the bed-plate P'.

Having described the specific parts of my gripping mechanism, I will now proceed and explain their mode of operation.

95 We will suppose the cable is going in the direction as indicated in Fig. 1, and the operating-lever L and pawl P are in the positions indicated in said figure; the car being at rest, the operator pulls back the lever. This will 100 have the effect of tilting the link Y so as to actuate the arms J K, throwing the former forward and the latter backward. This movement will cause the levers M and N to be actuated, bringing the former lever, with its binding-wheel, backward toward cable-carrying wheel *a*, and throwing the other lever, with its wheel *V*, toward the cable-carrying wheel *b*. The more the lever L is drawn back the greater will be the binding force or pressure 105 exerted on the cable, which is between said upper and lower wheels. When it is desired to stop the car, the lever L is pushed forward again to that point on the segment which will raise the wheels U and V from the cable and relieve it from the exerted pressure, the pawl P in the meantime having been drawn from the teeth by grasping the crank-lever F', in order to permit of the operating-lever being pushed forward; but while the car is progressing, as above described, should it become necessary, from any cause whatever, to disengage the cable from the carrying-wheels *a b*, the lever is pushed forward farther still. This will 115 have the effect of throwing up wheel U, and it, coming into contact with throw-out S', by means of the arm *n*, will raise it also. In Fig. 3 it will be seen that this operation is about to take place. As the ascent is being made, the inclined portion of the throw-out will 120 come into contact with the cable and force it from its seat on the carrying-wheel, and finally entirely off same, as indicated by the arrow and dotted lines in said Fig. 3.

115

120

125

130

While this is occurring, and simultaneously therewith, the heel y' on lever N will be thrown backward, striking and carrying with it in its downward course the free end of arm 5 g' . This movement will force up throw-out D', with the result heretofore mentioned. Now then suppose the cable has been replaced on the grip and the car has reached the terminus of the line and there is no turn-table, but the 10 car has to be run onto the return-track by means of any proper switch. What was before the front end of the car now becomes the rear. The cable is disengaged from the grip-frame, as before stated. The switch-plate is 15 then brought into contact with the cable and throws it over to that side of the car which was before the left, but which on the return-trip becomes the right. The cable is now brought so as to come into a right line with 20 the carrying-wheels on the side of the frame opposite to that on which it was before carried. A sheave in the cable-conduit, which is raised somewhat higher than the ordinary sheaves, holds the cable, and as the car is 25 moved onto the return-track the cable is on an incline until it finally finds a level and rests on the carrying-wheels of the grip-frame, when a purchase can be effected, as before described; but before this can be done the 30 gripman reverses the pawl P, seating it in that portion of the segment the teeth of which run in a direction opposite to that heretofore described. This reversal of the pawl is accomplished by raising the collar G from the 35 square or angular portion of the pawl, as indicated in Figs. 1, 2, and 4. There now being no hinderance, the pawl can be turned and placed in the desired position. This explanation will be more apparent by referring to 40 Figs. 2 and 4, where the pawl is shown in a position reverse to that shown in Fig. 1.

Of course where turn-tables are employed but one set of the carrying-wheels and their corresponding binding-rollers are used, there 45 being no occasion to shunt or change the cable from one side of the frame to the other, or disengage it at all from the grip, except when crossings are encountered or an accident occurs.

50 The grip herein shown and described is designed to be placed in and operated from the middle of the car; but, if desired, it may be placed on and operated from the ends either directly by the upright lever L and link Y, or 55 the mechanism can be operated through the instrumentality of draw-levers, such as are shown and described in my Patents Nos. 372,144 and 375,997.

Having thus described my invention, what I 60 claim as new, and desire to secure by Letters Patent, is—

1. In a grip for cable-railway cars, the throw-outs S' D', suitably secured to both sides of the grip-frame, the double binding-levers M 65 M' N N' and their attached rollers, the levers N N' being each provided with a heel which actuates an arm, g' , pivoted to throw-out D',

while throw-out S' is actuated through the arm n, in combination with arms J K, link Y, and lever L, connected together as shown and 70 described, and for the purposes specified.

2. In a grip for cable-railway cars, a segment-rack, as R, composed of two portions so connected together as to form a way in which the lever L can operate, the teeth of said rack 75 diverging in opposite directions from the center, in combination with reversible pawl P, removable collar G, rigid collar O', intermediate spring, p, stem C, and cranked lever F', pivoted to the lever L, all substantially as 80 shown and described, and for the purposes specified.

3. In a cable-grip, the toothed segment R, lever L, collars G and O', reversible pawl P, cranked lever F', stem C, and intermediate 85 spring, p, in combination with cross-plate H, link Y, arms J K, and their attached levers, which carry the binding-rollers, all arranged substantially as shown and described, and for the purposes noted. 90

4. A cable-gripper comprising the following elements: the frame A, carrying-wheels $a a'$ $b b'$, secured therein, and intermediate adjustable bed-plate, P', in combination with springs $l l$ and their accompanying throw-outs S' and 95 D' on either side of the frame, having arms $n g'$, all arranged substantially as shown and described, and for the purposes specified.

5. In a cable-gripper, the cross-plate S, to which the binding-levers and affixed rollers 100 are pivoted, in combination with guard-irons g g, throw-outs S' and D', stops c c, arms n and g' , and intermediate springs, ll, arranged substantially in the manner shown and described, and for the purposes specified. 105

6. The sliding collar G, capable of locking and unlocking the reversible pawl P, in combination with said pawl and operating-lever L, substantially as shown and described, and for the purposes noted. 110

7. The locking-collar G, reversible pawl P, and the operating-lever L, provided with stops, as i i, to limit the drop of said collar, substantially as shown. 115

8. A cable-grip comprising the following 115 elements: the frame A, carrying-wheels $a a'$ $b b'$, secured thereon, intermediate bed-plate, P', resting on set-screws e e, throw-outs S' D' on either side of the frame, the arms $n g'$, whereby said throw-outs are actuated through 120 the instrumentality of one of the binding-wheels, and a heel on one of the binding-levers, substantially as shown and described, and for the purposes noted. 125

9. The following elements in combination 125 in a grip for cable-railway cars: cable-carrying wheels located on either side of the grip-frame A, the binding-rollers U U' V V', also on either side of the frame and connected to levers M M' N N', which are actuated through 130 the instrumentality of arms J K, intermediate link, Y, and operating-lever L, in combination with a segment whose teeth are oppositely inclined for the reception of reversible pawl P,

which is held or released by collar G and operated by lever F' through the medium of stem C, substantially as shown and described, and for the purposes noted.

5 10. In a cable-grip, the cross-plates S, to which the binding levers and rollers are pivoted, in combination with guard-irons g g and throw-outs S' and D', arms n and g', and intermediate springs, l l, substantially as shown 10 and described.

11. The levers N and N', provided with a heel each, which actuate levers g' and operate throw-outs D', in combination with guard-irons g, springs l, and stop-pins c, substantially as shown and described, and for the purposes 15 noted.

BRADNER L. HARRIS.
